CHARLES L. POWELL, OF NEW YORK, N. Y., ASSIGNOR TO CAISSON CONTRACTING COMPANY, OF NEW YORK, N. Y., A CORPORATION OF DELAWARE

METHOD AND APPARATUS FOR FORMING FOUNDATION COLUMNS

Application filed March 16, 1932. Serial No. 599,073.

This invention pertains to the making of foundations and the like for buildings and other structures, particularly foundations of the concrete pier or column type which are sunk into the ground by pneumatic caissons in order to reach suitable footings.

As will appear from the following description, the invention provides a number of advantages over pneumatic caisson methods heretofore used.

The working chamber at the lower end of the caisson is of larger diameter than the shaft that extends up to ground level. This means that the only substantial frictional resistance encountered in sinking the caisson is that between the chamber and the wall of the excavation. The resistance is therefore held to a minimum, and is, furthermore, substantially constant, as distinguished from the usual practice, in which the caisson throughout its length is the full diameter of the hole whereby the frictional resistance increases with the depth of the excavation.

With the working chamber of larger diameter than the shaft, liquid such as water or mud-laden fluid may be used to fill the annular space above the working chamber, thus serving not only to decrease the additional load required for sinking but also to prevent caving of the walls of the hole above the working chamber.

The frictional resistance of the caisson is practically constant at all depths; and the weight of the shaft is almost as great per foot of length as its displacement. Consequently, if the method of lowering the air pressure temporarily, to drop the caisson, is used, friction should prevent uplift and therefore only a small amount of additional weight, if any, will be required.

The present invention permits raising and recovery of the working chamber and shaft during the concreting operation, the raising usually being accomplished by air pressure or by using air pressure to assist hoisting cables or jacks.

Further and other objects and advantages will be apparent from the specification and claims, and from the accompanying draw-

ings which illustrate what is now considered the preferred embodiment of the invention.

Fig. 1 shows the apparatus during the sinking of a hole.

Fig. 2 shows the apparatus after the hole has been sunk to rock, or other footing, and concreting begun.

Fig. 3 shows the concreting operation under way after removal of the man-and-material lock, the caisson being partly raised.

Fig. 4 shows the completed column or pier.

Fig. 5 shows the concrete hopper on the top of the shaft.

Fig. 6 shows an enlarged view of the man-and-material lock with the auxiliary shaft-sealing partition in broken lines.

Fig. 7 is an enlarged view of the sealing partition in operative position.

Fig. 8 is a view on line 8—8 of Fig. 7.

Referring to the drawings, the working chamber 20 of the caisson is provided with an upwardly extending man-and-material shaft 22. To begin operations the chamber is set in position on the ground surface or on the bed of a stream or other body of water, or on the bottom of a hole which may have been dug by any known method.

In any event after the chamber has been set in position with sufficient shafting to extend well above the starting surface, the hole is filled with liquid such as water or mud-laden fluid to balance the normal fluid pressure at the bottom of the working chamber and to prevent the walls of the hole from caving above the working chamber. A man-and-material lock 24 is attached to the top of the shaft and air pressure is admitted to shaft and chamber from hose 30 through valves 32 and 33, thus ejecting from the bottom of the working chamber all liquid which may have been therein. If flotation of the caisson impends (friction not being sufficient to hold the caisson down), enough weights 26 are placed on platform 28 (attached to the upper end of shaft 22) to prevent the lifting of the shaft and working chamber by otherwise unbalanced air pressure.

After the fluid is ejected from chamber and shaft, men with digging tools are lowered through the lock down the shaft into the working chamber.

The material they excavate is raised and dumped in the usual manner by bucket 34 on cable 36. Removal of material below the working chamber permits the chamber, shaft, 5 lock, etc., to sink under the influence of weights 26 or by a temporary release of the air pressure.

As the hole deepens it becomes necessary to lengthen shaft 22, which, for convenience, is 10 usually built up of short sections joined by flanges 38.

One method of changing the shaft length comprises simply removing the men and then flooding chamber and shaft with liquid to 15 equalize the pressure in the working chamber. The weights and platform, if used, and lock are then removed, the required section of shaft added, the lock, and, if necessary, the platform and weights replaced, and air 20 pressure applied to blow out the shaft and chamber again. The men are then returned to work.

Another method of changing the shaft length, when frictional resistance exceeds 25 buoyancy, is to place an auxiliary partition in the upper end of the shaft below the men as they come up the shaft. Sufficient air pressure is then maintained below that partition to prevent flooding of shaft and chamber 30 while the shaft changes are being made above. In Figs. 6, 7 and 8 one form of partition is shown. It comprises two half partitions 40 hinged together by hinges 42. Adjacent the hinges each half partition has a 35 downwardly projecting flange 44, and between the flanges, when the partition is in operative position, is a sheet of resilient packing 46 to prevent leakage of air. Around the outer edge of the upper side of the partition 40 is a ring 48 of resilient packing. Within the upper end of each section of shaft 22 is a steel ring 50. To apply the partition, it 40 is folded at the hinge, lowered below ring 50, and then raised by chains 52 into its operative 45 position (Fig. 7), and then air valve 54 and hose 56 are attached, through which air is supplied to the shaft and chamber below the partition. After the lock has been opened preparatory to its removal, the air pressure 50 below the partition serves to hold the partition in operative position without the assistance of chains 52. While removing the lock and attaching the new shaft section, hose 56 may be temporarily disconnected. It is 55 only necessary to have the hose connected sufficiently to replace any air which may leak slowly past partition 40.

After the lock is replaced and the pressure equalized, the partition may be removed.

60 The hole is thus excavated down to rock or other footing 58 after which the footing is prepared for concrete. After inspection, the men go out through the lock and the pouring of concrete begins. The concrete 59 is introduced through the concrete hopper 60

(Fig. 6) and door 62 on the lower end of the hopper in the usual manner. When the concrete has reached a sufficient height, the caisson is made slightly buoyant by removing 70 enough of the weights 26 or, if the frictional resistance has been sufficient to make the weights 26 unnecessary, by slightly increasing the air pressure to press downwardly against the concrete and upwardly against the caisson. The slightly buoyant caisson then rises. This rising may be controlled either by adding or removing enough of the weights 26 or by increasing or reducing the air pressure or by both. As the caisson is thus raised, more concrete is added until the caisson reaches a level where the weight of concrete, above the bottom edge of the working chamber, equals the external pressure there. When that level is reached, 75 weights 26, platform 28, concrete hopper 60, lock 24, and some of the shafting 22 are removed. Concrete hopper 60 is then connected directly to the top flange of the remaining shafting 22 and, air being admitted through pipe 66 (Figs. 3 and 5), the concreting 80 and raising process is resumed.

90 As the working chamber and shaft rise, the water or mud-laden fluid 68 surrounding the shaft is displaced out of the top of the hole. The shaft is successively shortened until the concrete in the excavation reaches the required height, whereupon the remainder of the shaft, and the working chamber are hoisted out of the hole, leaving the finished column as in Fig. 4.

100 The recovered work chamber and shaft may be re-used, as desired.

105 It is to be understood that the invention is not limited to the specific embodiment herein illustrated and described, but may be used in other ways without departure from its spirit as defined by the following claims.

I claim:

110 1. A caisson for sinking a hole in the ground, comprising in combination, a working chamber of substantially the diameter of the hole, a shaft of lesser diameter extending from the top of said chamber and being free of the walls of the hole, and means for preventing entrance of extraneous material into said caisson.

115 2. Apparatus for sinking a hole in the ground, comprising in combination, a working chamber of substantially the diameter of the hole, a shaft of lesser diameter extending from the top of said chamber and being free of the walls of the hole, and an airlock on the top of said shaft, substantially as described.

120 3. Apparatus for sinking a hole in the ground, comprising in combination, a working chamber, a shaft extending upwardly from said chamber, said shaft comprising comparatively short sections, each section having an internal circumferential band 125

therein, and a collapsible partition insertable through the top of said shaft to a position below any one of said bands and expansible thereunder and in contact therewith for providing a substantially airtight compartment below said partition.

4. In the method of digging a hole in the ground with a caisson, the steps of lowering the caisson as the digging proceeds and increasing the length thereof, and maintaining substantially constant frictional resistance between the caisson and walls of the hole.

5. In the method of digging a hole in the ground with a caisson, the steps of lowering the caisson as the digging proceeds and gradually increasing the length thereof, maintaining substantially constant frictional resistance between the caisson and walls of the hole and withdrawing the caisson after the hole is completed.

6. In the method of forming a concrete column in the ground with a caisson, the steps of lowering the caisson until a hole of the desired depth is provided, depositing plastic concrete in the interior of the caisson, and introducing fluid under pressure into said caisson above said concrete whereby said caisson is forced upwardly from said hole.

30 7. In the method of digging a hole in the ground, the steps of providing a caisson having a working chamber at its lower end and a shaft of less diameter than the chamber and free of the walls of the hole extending upwardly from said chamber and excavating the ground below said caisson until the chamber reaches the desired depth and filling the caisson with plastic concrete.

8. In the method of digging a hole in the ground, the steps of providing a caisson having a working chamber at its lower end and a shaft of less diameter than the chamber and free of the walls of the hole extending upwardly from said chamber, excavating the ground below said caisson until the chamber reaches the desired depth, introducing plastic concrete into the hole through said caisson, and withdrawing the caisson gradually as the introduction of concrete proceeds.

45 9. In the method of digging a hole in the ground, the steps of providing a caisson having a working chamber at its lower end and a shaft of less diameter than the chamber and free of the walls of the hole extending upwardly from said chamber, excavating the ground below said caisson until the chamber reaches the desired depth, introducing plastic concrete into the hole through said caisson, introducing fluid under pressure into said caisson above the concrete whereby the caisson is forced upwardly from the hole.

60 10. In the method of digging a hole in the ground, the steps of providing a caisson having a working chamber at its lower end

and a shaft of less diameter than the chamber and free of the walls of the hole extending upwardly from said chamber, excavating below the caisson whereby the caisson sinks into the ground, and applying an increasing load to the roof of the working chamber as the caisson sinks lower into the ground.

70 11. In the method of digging a hole in the ground, the steps of providing a caisson having a working chamber at its lower end and a shaft of less diameter than the chamber and free of the walls of the hole extending upwardly from said chamber, excavating below the caisson whereby the caisson sinks into the ground, and preventing collapse of the wall of the hole above said chamber by maintaining liquid in the hole above said chamber.

75 12. The method of sinking a caisson in the ground to form a hole, which consists in excavating the ground below said caisson, maintaining fluid pressure tending to lift said caisson, and applying a fluid load to said caisson within the hole tending to neutralize the pressure acting to lift the caisson.

80 13. The method of sinking a caisson in the ground to form a hole, which consists in excavating the ground below said caisson, maintaining fluid pressure within the caisson tending to lift said caisson, and maintaining a liquid load exterior of the caisson and within the hole tending to neutralize the action of the fluid pressure and preventing collapse of the wall of the hole.

85 In testimony whereof I hereto affix my signature.
